BUILDING CONSTRUCTION

Herman Timm, New York, N. Y.

Application July 5, 1934, Serial No. 733,848

1 Claim. (Cl. 72—46)

The main object of this invention is the provision of a novel construction for buildings, more particularly the provision of light and jointless walls for frame buildings.

5 Another object of the invention is the provision of such a wall construction whereby the building is made more nearly fireproof, and at the same time is better insulated so that its rooms are kept warmer in the winter and cooler in the summer.

10 Still another object of the invention is the provision of such a wall construction which is at the same time inexpensive in cost of manufacture and fabrication, and which considerably reduces the cost of erecting the building, as well as providing a considerable saving of time in the erection.

15 The above and other objects will become apparent in the description below, in which characters of reference refer to like-named parts in the accompanying drawing.

20 Referring briefly to the drawing, Figure 1 is a cross-sectional elevational view taken through an inside or partition wall, showing also sections of the floor and ceiling.

Figure 2 is a view taken at right angles to Figure 1, showing in cross-section an outside wall.

25 Figure 3 is a fragmentary view, partly in cross-section of the outside wall shown in Figure 2, showing the space behind the "Lally" column.

Figure 4 is an elevational view of a door frame, showing the anchors by means of which these walls are mounted thereabout.

30 Referring in detail to the drawing, the numerals 10 and 11 represent the floor-supporting joists resting on the foundation 12. The floor 13 rests on the joists 10 and 11. The usual "Lally" columns 16 extend at spaced-apart intervals from

the foundation, on which they rest, upward, and at their upper extremities they support the ends of steel I-beams 15, in which the ceiling joists 14 are supported.

5 The wall 19 (Figure 1) divides the room 17 from the room 18. The usual baseboards 20 edge the wall 19 at the floor 13, and the wall rests on a support 21 mounted on the joist 10. Each wall 19 comprises, at its core, a pair of wires 22 twisted together at their centers to form a cross. The wall or partition 19 is built around these wires 22 as a core, the composition of the wall being a mixture of cinders and plaster of Paris. Along the upper edge of the wall 19, a plurality of spaced-apart clamps 23 are imbedded in the wall, 10 and the ends 24 of these clamps are bent around the lower web of the I-beam to maintain the wall in erect position.

10 In Figure 4 the means of anchoring the walls 19 about a door frame 25 is illustrated, the T-shaped members 26 extending from all sides of the frame being imbedded in the walls 19.

15 Obviously, the material of which the walls is made may vary from that above-mentioned, and other modifications in form and structure may be 20 made without departing from the spirit of the invention.

I claim:

25 An improvement in building construction comprising, in combination with a ceiling I-beam, a 30 fabricated wall adapted to rest on the floor of the building, and clamps imbedded in the upper edge of said wall, said clamps having flexible arms extending from each side, said arms being bent upwardly and toward each other against the 35 web of said beam to lock said wall in erected vertical position.

HERMAN TIMM.
